CLAIM

The ornamental design for a hippo shaped camera bag, as shown and described.

DESCRIPTION

FIG. 1 is a front perspective view of a hippo shaped camera bag, showing my new design;

FIG. 2 is a front elevational view of the invention illustrated in FIG. 1;

FIG. 3 is a rear elevational view of the invention illustrated in FIG. 1, the broken lines representing environment and forming no part of the claimed design;

FIG. 4 is a top plan view of the invention illustrated in FIG. 1;

FIG. 5 is a bottom plan view of the invention illustrated in FIG. 1;

FIG. 6 is a left elevational view of the invention illustrated in FIG. 1; and,

FIG. 7 is a right elevational view of the invention illustrated in FIG. 1.
